UNITED STATES PATENT OFFICE.

JOHN W. FOLEY, OF BOGOTA, NEW JERSEY, ASSIGNOR TO WESTERN ELECTRIC COMPANY, INCORPORATED, OF NEW YORK, N. Y., A CORPORATION OF NEW YORK.

AMPLIFIER CIRCUITS.

Application filed January 18, 1926. Serial No. 82,079.

This invention relates to telephone subsets, and has for an object to provide means energized from a central source for amplifying the received, or both the received and 5 transmitted signals.

It is often desirable to equip a subscriber's set for amplifying received or both the received and transmitted signals. Electron discharge amplifiers are very suitable for 10 this apparatus and it is desirable that the devices be energized from a central source.

In accordance with a feature of this invention, a thermionic amplifier is provided for amplifying the received energy at a subscriber's set. Means are provided for supplying both the filament heating current and the space current to this device from a central source. In addition, current is supplied to the transmitter from the same source.

20 In accordance with another feature of this invention, a thermionic amplifier energized from a central source is provided for amplifying both the received and transmitted energies.

25 The invention will be more readily understood by reference to the following description in connection with the drawing in which: Figs. 1, 2, 3 and 4 show telephone systems embodying subscribers' sets arranged for amplifying the received signals; and Fig. 5 shows a system embodying a set arranged for amplifying both the received and transmitted signals.

In Fig. 1 the subscribers' sets A and B are 30 connected by lines 6 and 7 to a central station C which comprises the usual central stations equipment including a common battery 8 and repeating coil 9. At the subscriber's station A the telephone transmitter 11 of the push-pull type is operative through a repeating coil 12 to impress speech variations onto the line 6. An amplifier 13 is provided which is connected to the line 6 through the input transformer 14 and having a receiver 15 connected to its output terminals. The tube 13 is energized from the central source 8, condensers 16 and 17 and retard coil 18 being provided for controlling the paths of the circuit and signaling current in a manner described below. A switchhook 25 and a call bell 26 are also provided. The switchhook 25 operates to deenergize the tube 13 by breaking the filament circuit

when held in the down position by the weight of the receiver. The calling bell 26 is connected in series relation with the condenser 16 across line 6, the bell and condenser being so proportioned as to respond to currents of ringing frequencies sent over the line.

60 Transformer 14 is of the usual step-up type for efficiently operating the tube 13.

When the switchhook 25 is closed, direct current flows from the positive terminal of the battery 8 over line 6 through the two sides of transmitter 11 in parallel, transformer 12, rheostat 27, retard coil 18, filament 28 of the vacuum tube 13, grid biasing resistance 29 and the primary of transformer 14 back over line 6 to the negative terminal 70 of the battery 8. This current energizes the filament 28 and makes the transmitter 11 operative. The rheostat 27 is provided for the purpose of controlling the filament current of the tubes. The grid of the tube 75 13 is maintained at a negative potential with respect to the filament by the drop in the resistance 29.

75 The space current of the tube can be traced from the positive terminal of the battery 8 through the calling bell 26, the receiver 15 to the plate 30 of the tube 13, filament 28, resistance 29, primary winding of the transformer 14 and back over line 6 to the negative terminal of the battery. The inductive effect of the bell winding 26 prevents the flow of signaling current through this circuit. Condensers 16 and 17 provide paths 80 for the signaling current in the output circuit of the tube and the transmitter circuit 90 respectively, while at the same time confining the direct current in the plate and filament to the proper paths.

85 Subscriber set B is not shown in detail but may be similarly arranged or of any 95 suitable type.

90 Fig. 2 shows a similar system except that in this subset circuit a single acting transmitter 32 is provided in place of the push-pull transmitter 11. The central station C is merely indicated, the battery and repeating coils not being shown in detail. The direct current flow in this circuit may be traced 100 from the positive terminal of the central battery over the line 6 through switchhook 25, transmitter button 32, filament 28, resistance 105

29, primary winding of the transformer 14, rheostat 27 over line 6 back to the negative terminal of the central battery. The space current circuit is the same as that for the system shown in Fig. 1.

Fig. 3 shows an anti-side tone subscriber's set of the type shown in Fig. 5 of U. S. Patent 1,255,472 granted to G. A. Campbell, January 22, 1918. The element 33 is provided for balancing the line. It usually consists of a resistance and is incorporated in the transformer winding. When the transmitter 32 is operated, it energizes both windings 35 and 36 of the transformer 34, part of the energy being transmitted over the line 6 and the other part dissipated in the element 33. The current in these two windings being opposed, no energy is transmitted through the tube 13 to the receiver 15.

10 The filament heating circuit for this set may be traced from the positive terminal of the central battery over line 6 to switchhook 25 where it divides, the main portion flowing through the transmitter 32 while the rest flows through resistance 33 and winding 36 to the retard coil 18, filament 28, resistance 29, connection 37, rheostat 27 back over the line 6 to the negative terminal of the central battery. The plate current can be

15 traced from the positive terminal of the central battery over the line 6, through winding of the calling bell 26, receiver 15, anode 30, filament 28, resistance 29, connection 37, rheostat 27, back over the line 6 to the negative terminal of the central battery.

20 The set in Fig. 4 is similar to that of Fig. 3 except that the retard coil 18 is omitted, and part of the talking current is permitted to flow through the filament. In this case, the filament heating circuit may be traced from the positive terminal of the central battery over line 6, through switchhook 25, transmitter 32 in parallel with resistance 33 and winding 36 in series, winding 35 of the

25 primary winding of transformer 34, connection 38, filament 28, resistance 29, connection 37, rheostat 27, back over the line 6 to the negative terminal of the central battery.

30 The greater portion of the talking current flows through the low impedance path provided by the condenser 17 to winding 35 while the remainder flows through the parallel path provided by the filament 25 and resistance 29. In other respects, this set is the same as that shown in Fig. 3.

35 Fig. 5 shows a set arranged for amplifying both transmitted and received energy. The arrangement of this set is in general similar to that of the two-way one element type repeater circuit, the transmitter-receiver circuit 48 composed of the magnetic transmitter 39 and the receiver 15 connected in series to one winding of the transformer 40 being balanced against the line 6.

40 The filament heating current may be

traced from the positive circuit of the central battery over line 6, upper contact switchhook 25, rheostat 27, retard coil 18, filament 28, resistance 29, connection 47 back over line 6 to the negative terminal of central battery. The space current circuit may be traced from the positive terminal of the central battery over line 6 through the windings of the bell 26, primary of transformer 42, anode 30 of tube 13, filament 28, resistance 29, connection 47 back over the line 6 to the negative terminal of the central battery. Signaling current coming over the line 6 divides between the input and output circuits of the tube 13, that going to the output circuit of the tube 13 is dissipated while that going to the input circuit is amplified and impressed through the transformer 42 upon the line 6 and the winding 41 of transformer 40 in series. The impedance of the transmitter-receiver circuit 48 as seen through the transformer 41, being balanced with that of the line 6, there is no difference of potential between the terminals of the primary winding of input transformer 44 and, therefore, no amplified energy is fed back into the tube 13 so as to cause singing.

This invention is not limited to the embodiments shown which may be variously modified without departing from the spirit of the invention as defined in the appended claims.

What is claimed is:

1. In combination, an electron discharge device having input and output terminals, a space current circuit and a cathode heating circuit, a receiver connected to the output terminals of said device for receiving amplified signals therefrom, a source of direct current remote from said device, a line connecting said source and said device for supplying direct current and for transmitting signaling current to said device, means for connecting said discharge device to the line to amplify the incoming signals transmitted over said line, and connections for supplying direct current from said line to said space current circuit and said cathode heating circuit in parallel with each other.

2. A combination according to claim 1, and a telephone transmitter connected in series in the cathode heating circuit.

3. A combination according to claim 1, and a transformer for connecting the line to the input terminals of the device and having such a ratio as to step up the voltage of the line.

4. A telephone system comprising a central station having a source of direct current, a line from said station for supplying direct current and for transmitting signaling current, a telephone substation, comprising an electron discharge device having input and output terminals and a thermionic cathode, a receiver associated with the output terminals of said device, a transmitter,

5. The filament heating current may be

- connections from said line for supplying direct current to said transmitter and said cathode in series, said connections including an inductance for preventing the flow of signaling current therein, connections in parallel with a portion of said first connections including the inductance and the cathode for transmitting signaling current from said transmitter to said line, said last connections including a condenser to prevent the flow of direct current therein, connections from said line for supplying space current to said device, said connections including an inductance, and connections from said line to the input terminals of said device for supplying signaling current thereto.
5. A telephone system according to claim 4 in which the substation includes a transformer for connecting the line with the input terminals of the electron discharge device, and an impedance associated with a portion of the primary winding of said transformer for rendering said circuit anti-side tone.
- 10
- 15
- 20
- 25
- In witness whereof, I hereunto subscribe my name this 16th day of January, A. D., 1926.

JOHN W. FOLEY.
